PIVOTED JAW WRENCH ACTUATED BY
TORQUE-APPLYING EXTENSION HANDLE

Robert C. Knecht, Cleveland, Ohio

Application September 1, 1944; Serial No. 552,258

6 Claims. (Cl. 81—91)

1

My invention relates to tools in general and more particularly to a washing machine wrench to loosen the agitator post of a washing machine.

Washing machine repairmen are oftentimes required to remove the agitator post of a washing machine for repairs. This post is tightly threaded into a member from which it must be disengaged for repair work. As can be readily understood, a repairman cannot exert a great amount of twisting force to the post by reaching into the tub with an ordinary pipe wrench.

Therefore, an object of my invention is to provide a wrench to encompass the agitator post of a washing machine and engage the post by means of jaws pivotably mounted on the wrench.

Another object of my invention is to provide a wrench to encompass the agitator post of a washing machine and engage the post by means of jaws pivotably mounted on the wrench and having an extension handle positioned above the wrench for transferring a force applied to the handle exterior of the washing machine tub to the wrench gripping the agitator post inside the tub.

Another object of my invention is to provide a wrench to encompass the agitator post of a washing machine and engage the post by means of jaws pivotably mounted on the wrench with lever arms integrally connected to the jaws adjacent the area of the jaws which is disposed to contact the post.

Another object of my invention is to provide a wrench to encompass the agitator post of a washing machine and engage the post by means of jaws pivotably mounted on the wrench with lever arms integrally connected to the jaws adjacent the area of the jaws which is disposed to contact the post, and having adjustable locking means to hold the jaws in firm contact with the post.

Other objects and a fuller understanding of my invention may be had by referring to the following description and claims, taken in conjunction with the accompanying drawing, in which:

Figure 1 is a plan view of my improved washing machine wrench with the jaws thereof locked in contact with an agitator post;

Figure 2 is a side elevational view of my improved wrench with an extension handle engaging the wrench and extending above the wrench;

Figure 3 is a cross-sectional view of the adjustable lock means taken along the line 3—3 of Figure 1;

With reference to Figure 1, I illustrate a type of wrench conforming to my invention. The wrench comprises an annular member disposed

5 to encompass the agitator post 14 of a washing machine. Two jaws 12 are illustrated for engaging the post 14. The jaws 12 are pivotably mounted at diametrically opposite sides of the annular member by means of pivot bolt 15, whereby the jaws 12 may swing inwardly of the annular member to engage the post 14. With reference to Figure 2, it will be seen that the annular member is illustrated as comprising two 10 annular rings 10 and 11 which are rigidly connected to one another by spacer blocks 19. A rigid connection is maintained between the annular rings 10 and 11, and I illustrate a rivet 23 to rigidly connect the rings to the spacer blocks 19, although other fastening devices may be used. The form of the jaws 12 is best illustrated in Figure 1, and it can be seen that lever arms 16 are integrally attached thereto and extend outwardly from the annular rings. The lever arms 20 16 preferably are secured to the jaw members 12 adjacent to the area which is disposed to engage the posts.

A slideable block 22 for each jaw, as illustrated in cross-section in Figure 3, is slideable mounted 25 between the annular rings 10 and 11 and is provided with a threaded opening therethrough. A set screw or bolt 23 is threaded through the opening in the block 22 and may be tightened up against the jaw 12 with which it is cooperating to provide a constant pressure upon the jaw and hold it in contact with the post 14. In Figure 1, I illustrate the jaws 12 as each having a series of teeth 20 on the face of the jaw that engages the post 14 to provide a non-slipping engagement therebetween. I also illustrate a series of notches 21 on the opposite sides of the jaw to provide convenient contact surfaces for the set screws 23. However, the notches 21 are not necessarily indispensable and may be omitted if desired. In the case that the notches 21 are omitted, the bolts 23 are then disposed to contact the back of the jaw 12 at any point where the jaw 12 swings inwardly of the annular rings 10 and 11 far enough to admit the block 22 to slide between the jaw and the rings.

With reference to Figure 2, I illustrate a handle referred to generally by the reference character 13. The handle 13 is used to provide an extension grip on the lever arms 16, whereby service men using the wrench need not reach down into the tub of the washing machine or other enclosures where the wrench is to be used. This handle 50 13 comprises two upright extension arms 17 to which a bar 18 may be secured by any suitable means, such as by welding. The free ends of the

extension arms 17 are preferably slotted to provide forks which may be slipped respectively over the lever arms 16 and thus provide turning engagement between the arms 16 and the handle 13.

For operation, the jaws 12 of the wrench are swung outwardly far enough to pass over the post 14 and the entire wrench is placed down upon the post 14 with the rings 10 and 11 encompassing the post. The jaws 12 may then be brought into engagement with the post 14 by respectively moving the slidable blocks 22 into a convenient position, and tightening the set screws 23 tightly against convenient notches 21 until the teeth 20 of the jaws 12 are pressing tightly against the post 14. It will be noticed, that with the wrench in the position as illustrated, and looking downwardly upon the post 14, in Figure 1, the wrench is in position to turn the post 14 in a clockwise direction to tighten same, the post being provided with right hand threads. However, to loosen the post 14, the wrench may be turned upside down from the position illustrated, and then will be in position to turn the post 14 in a counterclockwise direction, which is the direction for loosening a post equipped with right-hand threads.

To use the handle 13, the forked ends of the arms 17 are extended over the lever arms 16 of the jaws 12 with the cross-bar 18 positioned above the wrench as illustrated in Figure 2. The post 14 is then turned by exerting a rotary force upon the bar 18 in the direction in which it is desired that the shaft should turn. The greater the rotary force which is exerted to turn the post, the greater the pressure of the jaws against the post to prevent the jaws from loosening their grip and slipping. My wrench is sturdy and will withstand an extraordinary amount of turning to unloosen a hard set post.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A wrench to turn the agitator post of a washing machine, said wrench comprising an annular member disposed to encompass said post, said annular member comprising two annular rings and spacer means therebetween for spacing the annular rings from one another, at least a first and a second jaw member for engaging the post, pivotal mounting means located between the annular rings at opposite sides of the annular member to pivotably mount the jaws, and jaws being pivotably mounted at one end thereof and being disposed to swing inwardly of the annular member to engage the opposite sides of said post, and lever arms connected to said jaws a distance away from said pivotal mounting means whereby force applied to said lever arms presses the jaws into engagement with said agitator post, and lock means for pressing the said jaws into constant engagement with said post, each lock means comprising a slidably mounted block member between said rings, said block member having a threaded opening therethrough and a threadable set screw to threadably engage said threaded opening and contact said jaws.

2. A wrench to turn the agitator post of a washing machine, said wrench comprising an annular member disposed to encompass said post, at least a first and a second jaw member each having

post engaging teeth for engaging said post and having lock-engaging notches on the opposite side thereof, pivotal mounting means at opposite sides of the annular member to pivotably mount the jaws, said jaws being disposed to swing inwardly of the annular member and engage opposite sides of said post, and lever arms connected to said jaws and extending outwardly from said annular member, whereby force applied to said extension arms presses the jaws into engagement with said agitator post, and lock means for pressing the at least a first and second jaw into constant engagement with said post, each lock means comprising a block member slidably carried by said annular member, said block member having a threaded opening therethrough, and a threadable element to threadably engage said threaded opening and contact said lock engaging notches on said jaws.

3. A wrench to turn the agitator post of a washing machine, said wrench comprising an annular member disposed to encompass said post, said annular member comprising two annular rings and spacer means therebetween for spacing the annular rings from one another, at least a first and a second arcuate jaw member, each having a pivot end and a tip end with a central portion therebetween, said jaw members being capable of gripping many different diameter posts with at least the central portion of the jaws engaging the posts, pivotal mounting means located between the annular rings at opposite sides of the annular member to pivotably mount the pivot ends of the jaws, said jaws being disposed to swing inwardly of the annular member to grip said opposite sides of said post, and lever arms connected to said jaws adjacent said central portion of the jaws, whereby force applied to said extension arms in the plane of the swing of the jaws presses the jaws into engagement with said agitator post.

4. A wrench to turn a turnable element, said wrench comprising an annular member disposed to encompass said turnable element, said annular member comprising two annular rings and spacer means therebetween for spacing the annular rings from one another, at least a first and a second jaw member for gripping the turnable element, each of said jaw members having a pivot end and a tip end, pivotal mounting means located between the annular rings at opposite sides of the annular member to pivotably mount the pivot end of the jaws, said jaws being disposed to swing inwardly of the annular member to engage the opposite sides of said turnable element, and lever arms connected to said jaws a distance away from said pivotal mounting means intermediate said pivot and tip ends, whereby force applied to said lever arms in the plane of the swing of the jaws presses the jaws into engagement with said turnable element.

5. A wrench to turn a turnable element in a recess, said wrench comprising an annular member disposed to encompass said turnable element, at least a first and a second jaw member for engaging the turnable element, pivotal mounting means located at opposite sides of the annular member to pivotably mount the jaws, said jaws being pivotably mounted at one end thereof and being disposed to swing inwardly of the annular member to engage the opposite sides of said turnable element, lever arms connected to said jaws a distance away from said pivotal mounting means, and a handle extension to engage said lever arms, said handle extension comprising at least a first and second upright extension arm each having interlocking surfaces to engage the

lever arms connected to said at least a first and second jaw member respectively, and a connecting member to extend between the uppermost portion of the upright extension and form a gripping handle, said handle extension serving to transmit a remotely applied force to said lever arms in said recess, whereby force applied to said gripping handle is transmitted to said lever arms and presses the jaws into engagement with said turnable element.

6. A wrench to turn a turnable element, said wrench comprising an annular member disposed to encompass said turnable element, at least a first and a second jaw member for gripping said turnable element, each said jaw member having a pivot end and a tip end, pivotal mounting means at opposite sides of the annular member to pivotably mount the pivot end of the jaws, said jaws being disposed to swing inwardly of the annular member and engage opposite sides of said turnable element, and lever arms connected to said

jaws a distance away from said pivotal mounting means intermediate said pivot and tip ends and extending outwardly from said annular members.
